MEANS FOR FLOWING WELLS

Feri A. Thaheld, Dallas, Tex., assignor to The
Guiberson Corporation, Dallas, Tex., a corpora-
tion of Delaware

Application March 30, 1936, Serial No. 71,669

11 Claims. (Cl. 103—232)

This invention relates to new and useful im-
provements in means for flowing wells.

One object of the invention is to provide an im-
proved flow device which is particularly adapted
5 for use in lifting well fluids to the surface.

An important object of the invention is to pro-
vide an improved well flow device wherein the well
fluid is metered and controlled in accordance
with the pressure of the lifting fluid, whereby said
10 well liquid may be lifted to the surface by a com-
paratively low pressure.

Another object of the invention is to provide an
improved flow device having a piston exposed to
15 the pressure of the lifting fluid for controlling the
inlet of said fluid into the well tubing, said piston
also controlling the inlet of the well liquid into
the tubing, whereby the building up of a static
head of liquid within the tubing above the flow
device is prevented.

20 Another object of the invention is to provide
an improved flow device arranged to be lowered
to the bottom of the well casing which is so con-
structed that the liquid will be raised in the well
tubing as soon as the lifting fluid is injected.

25 Another object of the invention is to provide an
improved system of flowing wells having casing
and tubing therein which consists in, packing off
the space between the well tubing and casing, in-
troducing a lifting pressure fluid into the casing
30 above the packer, controlling the inlet of the well
liquid to the tubing in accordance with the pres-
sure of the lifting fluid, introducing the lifting
fluid into the tubing after a column of well liquid
has been built up therein, and simultaneously cut-
35 ting off the flow of both well liquid and lifting
fluid to the tubing when the pressure of the lift-
ing fluid drops to a predetermined point.

40 A construction designed to carry out the inven-
tion will be hereinafter described, together with
other features of the invention.

The invention will be more readily understood
from a reading of the following specification and
by reference to the accompanying drawings, in
which an example of the invention is shown, and
45 wherein:

Figure 1 is a view, partly in elevation and partly
in section showing a flow device positioned within
a well casing.

Figure 2 is an enlarged transverse, vertical sec-
50 tional view of the flow device, and showing the
control piston in its lowered, or shut-off position.

Figure 3 is a view, similar to Figure 2 with the
piston raised.

Figure 4 is a horizontal, cross-sectional view,
55 taken on the line 4—4 of Figure 2.

Figure 5 is a horizontal, cross-sectional view,
taken on the line 5—5 of Figure 2.

Figure 6 is a horizontal, cross-sectional view,
taken on the line 6—6 of Figure 2, and

Figure 7 is a horizontal, cross-sectional view, 5
taken on the line 7—7 of Figure 2.

In the drawings, the numeral 10 designates an
elongate, tubular body which has its upper end
threaded at 11, whereby the usual coupling collar
12 may be screwed thereon. The upper end of 10
the collar receives the lower end of the well tubing
A and it is preferable that the body have the
same diameter as the well tubing. However, this
is not essential as said diameter may be less or
greater, as desired. The lower end of the body 15
is threaded to receive a collar 13 which is screwed
thereon.

A suitable packing assembly 14 is mounted on
the body at the lower end thereof. The packing
assembly may be of any suitable type but I prefer 20
to provide an offset or annular shoulder 15 on the
surface of the body whereby a cone 16 which sur-
rounds the body may be supported. An elastic
packing element or member 17 rests on the upper
end of the cone and surrounds the body. The 25
packing element is held in contact with the upper
end of the cone by an annular flange or cap 18
which engages the upper end of said packing ele-
ment, and which is preferably made integral with
the body 10. 30

Suitable gripping slips 19 are slidable vertically
on the cone 16 and it is obvious that when they
are in their upper position (Figure 2) said slips
will engage the casing wall. Each slip is carried
by a spring member 20 which has its lower end
secured to the lower end of a cage 21 which is
slidable on the body beneath the cone. The lower
end of the cage is provided with a hook 22 which
is arranged to engage a pin 23 extending radially
from the body, whereby the cage may be locked 40
to said body so as to move therewith. Suitable
friction springs 24 have their upper ends fastened
to the upper end of the cage 21, while their lower
ends are secured to a collar 25 slidable on the body
above the collar 13 at the lower end thereof. 45
When the hook 22 of the cage is engaged with the
pin 23 on the body, whereby the body and sleeve
move as a unit, it will be obvious that the slips 19
carried by the members 20 which are secured to
the cage will be in their lowered position on the 50
cone 16. Thus, in this position, said slips are dis-
engaged or out of contact with the casing wall.
The packing element 17 is set in the usual way.
The body is lowered into the well casing B with
the hooks 22 of the cage engaging the pin 23 on 55
the cone 16.

the body, whereby the slips are held in their lowered position on the cone during the lowering operation. At such time the packing element is in its normal position which is disengaged from the casing wall. When the body has been lowered to the bottom of the well casing, and it is desired to set the packing element 17, it is only necessary to rotate said body so that the pin 23 disengages the hook 22 of the cage. The body 10 is then moved downwardly a short distance, and the friction springs 24 serve to hold the cage and gripping slips 19 stationary, whereby the body 10 may move downwardly through the cage. As this occurs, the gripping slips 19 will ride up the inclined sides of the cone 16 and will move into engagement with the casing wall to prevent further downward movement of said cone. Continued movement of the body will cause the annular flange or cap 18 to distort the packing element 17 into engagement with the wall of the well casing B, whereby the space between the body and the casing is packed off.

A transverse spider 26 extends across the lower end of the body 10 and is provided with an axial solid hub 27. A metering pin 28 extends upwardly from the upper end of the hub and is preferably made integral therewith. The base of the pin has a diameter which is smaller than the diameter of the hub whereby an annular shoulder or seat 29 is formed around said pin. An elongate tubular piston rod 30 has its lower end engaging over the metering pin 28 and is movable vertically within the body 10. The upper end of the piston rod extends through a transverse guide member or plate 31 which is disposed across the interior of the body 10. The extreme upper end of said rod is connected with a vertically movable piston 32 which has a sliding fit within the body 10. The piston is normally held in its lower position with the lower end of the piston rod 30 resting on the seat, by a coil spring 33. This spring has its lower end resting on the upper end of the piston, while its upper end engages beneath an annular shoulder or ring 34 which is formed on the inner periphery of the body 10.

With such arrangement, it is obvious that the spring 33 will normally hold the piston in its lowered position so that the lower end of the piston rod 30 engages the annular seat 29 and prevents any flow of well liquid upwardly through the piston rod and piston and into the tubing A thereabove. Between the upper end of the packing element 17 and the underside of the piston 32, a radial port 35 is provided in the wall of the body 10, whereby a communication is established between the casing B and the interior of the body 10.

When the device or assembly is lowered into the well casing B to the lower end thereof, the packer assembly is set by rotating the body 10 so that the pin 23 on the body disengages the hook 22 of the cage 21. This permits the slips 19 to engage the casing wall and prevent further lowering of the cone 16. The weight of the body 10 and the tubing A will then distort the packing element 17, whereby the space between the casing and the body is packed off (Figure 2). Air, gas, or other lifting fluid is then introduced into the casing through the casing head C at the upper end thereof, through an inlet pipe 36. The lifting fluid will pass downwardly between the casing and tubing and will finally enter the radial ports 35 in the wall of the body 10 above the packing element 17. The pressure of this

lifting fluid entering the body 10 below the piston 32 will raise said piston upwardly against the pressure of the coil spring 33. As the piston 32 begins to move upwardly, the lower end of the piston rod 30 will ride upwardly with relation to the metering pin 28 whereby a flow of well liquid will pass upwardly through the tubular piston rod and the piston. Thus, it will be seen that as said piston is moved upwardly, the well liquid will flow upwardly into the tubing A. 10

For utilizing the lifting fluid which has entered the body 10 below the piston, to lift the well liquid which enters through the piston rod, a by-pass 37 is provided. This by-pass is located on the exterior wall of the body 10 and, as is clearly shown in Figure 2, is disposed opposite the coil spring 33 when the piston is in a lowered position. The by-pass includes a semi-circular casing 38 which forms a passage between a pair of ports or openings 39 and 40 which are formed in the body 10. By observing Figure 2, it will be seen that these ports are located above the piston 32 when the latter is in its lowered position.

After the lifting fluid which is within the casing B has entered the ports 35 and the piston 32 begins to move upwardly, it will be seen that the well liquid is permitted to flow into the tubing, as has been explained. Continued upward movement of the piston 32 against the pressure of the spring 33, will cause said piston to move 30 upwardly past the lower opening 39 of the by-pass, as is shown in Figure 3. By the time the piston has moved to this position, sufficient well liquid has entered the tubing A. As soon as the opening 39 is uncovered the lifting fluid from the well casing then passes through the opening 39 into the casing 38 of the by-pass. From this casing this lifting fluid flows through the opening 40 and into the body 10 above the piston. This lifting fluid then serves to aerate the column of well liquid which has entered the tubing above the piston, whereby this column of fluid is lifted to the surface. As soon as the lifting fluid is cut off after the column has been lifted, the pressure of said fluid within the well casing will immediately decrease. This will permit the coil spring 33 to immediately return the piston to its lowermost position, thereby cutting off the lifting fluid entering the well tubing, as well as causing the piston rod 30 to engage the seat 29 to shut off the flow of the well liquid. 45

From the above it will be seen that whenever the lifting fluid in the well casing is shut off, the flow of well liquid into the tubing is also automatically shut off. This prevents the building up of a static head of well liquid above the piston and, therefore, a very low pressure of lifting fluid, may be utilized in raising a column of well liquid. The metering pin 28 is curved so that at the beginning of the piston movement the flow of well liquid is slight. After the pressure of the lifting fluid within the well casing has built up sufficiently to raise the piston past the lower opening 39 of the by-pass, the lower end of the piston rod has moved above the metering pin 28 60 (Figure 3), whereby the flow of the well liquid is unobstructed. Thus, it will be seen that the provision of the metering pin permits an automatic regulation of the flow of well liquid in accordance with the pressure of the lifting fluid. It is again pointed out that as soon as the lifting fluid pressure decreases the flow of well liquid is immediately shut off. It is noted that the piston which is slidable within the body 10 is protected from the pressure of the well liquid by the trans-

verse partition 31 and thus, said piston is not subjected to the abrasive action of the flowing well liquid. The packing assembly 14, which has been shown, is one which may be purchased on the open market, and it is obvious that the invention is not to be limited to this particular type of packing assembly as any type suitable for the purpose may be employed.

What I claim and desire to secure by Letters 10 Patent, is:

1. In combination with a well tubing and casing, a support adapted to be connected with the well tubing and forming a continuation thereof, means for packing off the space between the well 15 tubing and well casing, means for introducing a lifting fluid into the well casing above the packing means, the support having an admission port and a bypass for establishing communication between the interior of the casing and the 20 tubing, movable means including a piston within the support for controlling the flow of lifting fluid through the bypass to the tubing, said admission port being located below the piston and a valve seat at the lower end of the support co- 25 acting with the movable means whereby said means also controls the flow of well liquid from the bottom of the hole into the tubing.

2. In combination with a well tubing and casing, a tubular body adapted to be connected with the well tubing and lowered into the well casing, means on the body for packing off between said body and casing, means for introducing lifting pressure fluid into the well casing, said body having an opening above the packing means 35 whereby the lifting fluid may enter therein, movable means within the body and actuated by the pressure fluid in the casing for controlling the admittance of lifting fluid into the tubing, and a valve seat at the lower end of the body co-acting 40 with the movable means, whereby said means also controls the flow of well liquid from the bottom of the hole into the well tubing.

3. In combination with a well tubing and casing, a tubular body adapted to be connected with the well tubing and lowered into the well casing, means on the body for packing off between said body and casing, means for introducing lifting pressure fluid into the well casing, said body having an opening above the packing means 45 whereby the lifting fluid may enter therein, movable means within the body and actuated by the pressure fluid in the casing for controlling the admittance of lifting fluid into the tubing, a valve seat at the lower end of the body co-acting 50 with the movable means, whereby said means also controls the flow of well liquid from the bottom of the hole into the well tubing, and resilient means for resisting the movement of said movable means until a predetermined pressure of 55 the lifting fluid is reached.

4. In combination with a well tubing and casing, a support adapted to be connected with a well tubing, means for packing off the space between the well tubing and well casing, means 60 for introducing a lifting fluid into the well casing above the packing means, the support having an admission port for establishing communication between the interior of the casing and the tubing, a movable piston within the support and actuated by the pressure of the lifting fluid in the well 65 casing for controlling the flow through the port to the tubing, and a liquid control valve actuated by the movable piston whereby the flow of well liquid from the bottom of the hole into 70 the tubing is controlled.

5. In combination with a well tubing and casing, a tubular body adapted to be connected with the well tubing and lowered into the well casing, means on the body for packing off between said body and casing, means for introducing lifting pressure fluid into the well casing, said body having an opening above the packing means 75 whereby the lifting fluid may enter therein, a movable piston within the support and actuated by the pressure of the lifting fluid in the well 80 casing for controlling the flow through the port to the tubing, and a liquid control valve actuated by the movable piston whereby the flow of well liquid from the bottom of the hole into the tubing is controlled.

6. In combination with a well tubing and casing, a support adapted to be connected with a well tubing, means for packing off the space between the well tubing and well casing, means for introducing a lifting fluid into the well casing above the packing means, the support having an admission port for establishing communication between the interior of the casing and the tubing, a movable piston within the support and actuated by the pressure of the lifting fluid in the well 20 casing for controlling the flow through the port to the tubing, a liquid control valve actuated by the movable piston whereby the flow of well liquid from the bottom of the hole into the tubing is controlled, and resilient means for resisting 25 the movement of said movable means until a predetermined pressure of the lifting fluid is had.

7. In combination with a well tubing and casing, a tubular body adapted to be connected with the well tubing and lowered into the well casing, means on the body for packing off between said body and casing, means for introducing lifting pressure fluid into the well casing, said body having an opening above the packing means 35 whereby the lifting fluid may enter therein, a movable piston within the support and actuated by the pressure of the lifting fluid in the well 40 casing for controlling the flow through the opening to the tubing, a liquid control valve actuated by the movable piston whereby the flow of well liquid from the bottom of the hole into the tubing is controlled, and resilient means for resisting the movement of said movable means until a predetermined pressure of the lifting fluid is had.

8. In combination with a well tubing and casing, a tubular body adapted to be connected with the well tubing and lowered into the well casing, means on the body for packing off between said body and casing, means for introducing lifting pressure fluid into the well casing, said body having an opening above the packing means whereby the lifting fluid may enter therein, a movable piston within the body and actuated by the pressure fluid for controlling the admittance 55 of lifting fluid into the tubing, a liquid control valve actuated by the piston for controlling the flow of well liquid from the bottom of the hole into the well tubing, and a coiled spring for resisting the actuation of the piston until a predetermined pressure of the lifting fluid is reached, said spring also serving as a means to simultaneously operate the liquid control valve to cut off the flow of well liquid and to move said piston to cut off the admission of lifting fluid to 60 the well tubing when the pressure of the lifting fluid decreases.

9. In combination with a well tubing and casing, a support adapted to be connected with the well tubing, means for packing off the space be- 75

tween the well tubing and casing, means for introducing a lifting fluid into the well casing above the packing means, a movable piston within the support and actuated by the pressure of 5 the lifting fluid for controlling the admittance of lifting fluid into the well tubing, a liquid valve actuated by the piston for controlling the flow of the well liquid from the bottom of the hole into the tubing, and a coiled spring for resisting the 10 actuation of the piston until a predetermined pressure of the lifting fluid is reached, said spring also serving as a means to simultaneously operate the liquid control valve to cut off the flow of well liquid and to move said piston to cut off 15 the admission of lifting fluid to the well tubing when the pressure of the lifting fluid decreases.

10. In combination with a well tubing and casing, a support adapted to be connected with a well tubing, means for packing off the space between 20 the well tubing and well casing, means for introducing a lifting fluid into the well casing above the packing means, the support having an admission port for establishing communication between the interior of the casing and the 25 tubing, a spring controlled movable means within

the support for controlling the flow of lifting fluid through the port to the tubing, a valve seat at the lower end of the support co-acting with the movable means whereby said means also controls the flow of well liquid from the bottom of the hole into the tubing, and means for metering the flow of well liquid through the valve. 5

11. In combination with a well tubing and casing, a tubular body adapted to be connected with the well tubing and lowered into the well casing, 10 means on the body for packing off between said body and casing, means for introducing lifting pressure fluid into the well casing, said body having an opening above the packing means whereby the lifting fluid may enter therein, movable 15 means within the body and actuated by the pressure fluid in the casing for controlling the admittance of lifting fluid into the tubing, a valve seat at the lower end of the body coacting with the movable means, whereby said means also controls the flow of well liquid from the bottom of the hole into the well tubing, and means for metering the flow of well liquid through the valve. 20

FERI A. THAHELD. 21
